An electronic module socket is provided having corresponding pairs of contacts wherein the contacts short out and are self-cleaning. A first contact having a semi-circle terminal end portion and a second contact having a J-shaped terminal end portion. The two terminal portions, upon removal of a module, slide past each other in opposite directions. The contacts having board contact points removed from the short out portions of the contacts. The contacts being fabricated in order to provide for gang loading of the contacts within the electronic module socket insulator.

FIG 1

FIG 4

FIG 5

ELECTRONIC MODULE SOCKET WITH SELF-CLEANING SHORTING CONTACTS

BACKGROUND OF THE INVENTION

This invention relates to electrical connectors and, in particular, an electronic module socket having self-cleaning shorting contacts.

Electronic module sockets having contacts which short out upon removal of an electronic module or printed circuit board from between the contacts are common. An electronic module or printed circuit board may be inserted into an electronic module socket between opposed pairs of contacts. The contacts are formed in such a way so that prior to insertion of a module, the opposed pairs of contacts have shorting portions which abut against each other. Upon insertion of the module, the module separates the two opposed pairs of shorting portions and contact the conductors of the board. The shorting area and the module contact area of the contacts of the prior art are generally located in the same position on the contact. Upon removal of the board and contact of the shorting portions of the opposed pairs of contacts, a short out between the contacts occurs, so that the electronic module socket may still be connected in series.

Such shorting contacts have the disadvantage that the contacts fail to short out when a build-up of glass flakes and/or debris from a module gathers on the shorting portions. Such a build-up prohibits the metal-to-metal abutment of the shorting portions of opposite pairs of contacts. It is common for the module being inserted in such electronic module sockets to comprise an epoxy glass board with unfinished chamfered edges. In situations where hundreds of insertions of the module into the electronic module socket occur, glass flakes from the module and/or debris may build-up on the shorting portion of the contacts. Such a build-up inhibits the contacts from shorting out after hundreds of insertions of the module.

It is therefore an object of the present invention to provide a shorting contact which avoids the build-up of glass flakes and/or debris at the shorting portions.

It is another object of the present invention to provide contacts which achieve a sufficient normal force to ensure short out and in contacting an inserted module within an electronic module socket.

It is a further object of the present invention to provide shorting contacts which can withstand hundreds of insertions of a module without inhibiting the shorting out feature.

It is another object of the present invention to provide a contact which may be manufactured on a single progressive die.

It is a further object of the present invention to provide contacts which may be loaded to an electronic module socket quickly, inexpensively and uniformly.

It is another object of the present invention to provide contacts which are self-cleaning.

It is a further object of the present invention to provide contacts which at rest are separated sufficiently to avoid the collection of debris therebetween.

SUMMARY OF THE INVENTION

The above objects are provided by an electronic module socket comprising an elongated insulative housing including an elongated central cavity for receiving an electronic module having a plurality of opposed pairs of contacts located along both sides of the central cavity. The contacts are

correspondingly and nonuniformly shaped so that upon removal of the printed circuit board from between the corresponding contacts, the terminal ends of the contacts automatically wipe against one another and provide a short out connection area. A first contact includes a mast section attached to a turn back loop section. The turn back loop section is attached to a terminal section having a semi-circular shape. An apex of the semi-circular terminal section of the first contact provides for a point of contact with the corresponding second contact. The terminal section is adjacent to a first module contact area.

The second contact includes a mast section connected to a turn back loop section. The turn back loop section connects to a second module contact section. The second module contact section attaches to a J-shaped terminal section. The terminal section of the second contact includes a flat area for contacting the corresponding apex section of the terminal section of the first contact. The first and second contacts being mounted opposite each other along the length of the electronic module socket insulator. The contacts alternate in their orientation along the insulator.

The first contact includes a first module contact area adjacent the semi-circle section. The second contact includes a second module contact area. The first module contact area is offset from the second module contact area. The first and second contacts include contact tails for throughboard or surface mounting. An alternative embodiment of the invention is provided wherein the insulative housing includes retention members for prohibiting the contacts from shorting out. The contacts are manufactured via a single progressive die.

Short out connection areas of the terminal sections are positioned away from the plane of insertion of the module and do not contact the module upon its insertion.

These and other features of the invention are set forth below in the following detailed description of the presently preferred embodiments.

BRIEF DESCRIPTION OF THE DRAWINGS

FIG. 1 is a side elevation cut-away view of an electronic module socket prior to insertion of an electronic module;

FIG. 2 is a side elevation cut-away view of an electronic module socket during insertion of an electronic module;

FIG. 3 is a side elevation cut-away view of an electronic module socket after insertion of an electronic module;

FIG. 4 is an enlarged side view of the contacts of an electronic module socket; and

FIG. 5 is a side elevation cut-away view of an alternative embodiment of an electronic module socket.

DETAILED DESCRIPTION OF THE PRESENTLY PREFERRED EMBODIMENTS

The present invention relates to an electronic module socket as shown in FIGS. 1-5. FIG. 1 is a side elevation cut-away view of an electronic module socket 10, including an elongated insulator body 12. Mounted in the insulator 12 is first contact 13 and second contact 23. Multiple opposed contacts are mounted along the sides of an elongated central cavity 11, and first contact 13 and second contact 23 will be discussed representatively. The first and second contacts 13,23 have terminal sections 16,26 at which contact is made between the first contact 13 and second contact 23. The contacts 13,23 are shaped so that when at rest, the pairs of corresponding contacts 13,23 are shorted out. This short out

feature allows for the contacts to be connected in series.

An electronic module **30** is inserted between contacts **13,23**. In a preferred embodiment, the electronic module **30** is a dual read out printed circuit board. The module **30** includes a circuit board having a first conductive surface **31** and a second conductive surface **32**. The electronic module **30** is comprised of a substrate of a polymer material. In a preferred embodiment, the electronic module **30** is G-10 epoxy glass. The electronic module **30** includes a chamfered edge **34**. The chamfered edge **34** is formed by use of a router or the like on the epoxy glass material. This may leave a rough unfinished edge which creates glass flakes when the chamfered edge **34** is rubbed against a surface.

FIG. 2 shows the electronic module **30** being inserted between contacts **13,23**. As the electronic module **30** is inserted, the chamfered edge **34** abuttingly slides against contacts **13,23** and forces terminal section **16,26** apart. As the electronic module **30** is inserted into the central cavity **11**, it slides against the contacts **13,23** and most of the glass flakes from the chamfered edge **34** are removed from the electronic module **30** and become deposited first at the module contact areas **15,25** and to a smaller degree at the terminal sections **16,26** of the contacts **13,23**.

FIG. 3 shows the electronic module **30** in its fully inserted position within electronic module socket **10**. Upon complete insertion, the first conductive surface **31** is contacted by first module contact area **15** of first contact **13**. Second conductive surface **32** is contacted by second module contact area **25** of second contact **23**. Tail sections **18** and **28** of first and second contacts **13,23**, respectively, protrude from the base of the insulator **12** and connect the conductive areas **31,32** of the electronic module **30** through the contacts **13,23** to a motherboard (not shown) to which the electronic module socket **10** is mounted. In a preferred embodiment, the contact tails **18,28** are throughboard mounted and soldered to the motherboard. In an alternative embodiment, the contact tails may be oriented for surface mounting.

It can be seen that the first module contact area **15** makes contact with conductive area **31** at a position lower than the position at which the second module contact area **25** abuts conductive section **32**. Due to the shape of the contacts, in order to provide an automatic wiping action, the module contact areas **15,25** of the contacts are off-set and not uniformly oriented directly across from one another. Due to the off-set module contact areas **15,25**, the contacts **13,23** are mounted alternatingly within the insulator **12**. Multiple contacts are mounted along a first side **35** of the insulator **12** and a second side **36**. The contacts are mounted alternatingly along the first side **35** so that a first contact **13** is next to a second contact **23** which is next to a first contact **13** and so on. On the second side **36** of the insulator **12**, a second contact **23** is mounted correspondingly and across from a first contact **13** on the first side **35**. Next to the second contact **23** is mounted a first contact **13** and next to that contact is mounted a second contact **23**, and so on. This alternating arrangement of contact pairs will ensure that the offset module contact areas **15,25** do not force the electronic module **30** to tilt in either direction within the electronic module socket **10**. This high/low, low/high alternating orientation of board contact areas **15,25** of the contacts **13,23** along the first and second sides **35,36** of the insulator ensure that the electronic module **30** will stand straight up in a parallel plane to the insulator walls of the elongated central cavity **11**.

A further improvement of this invention is the production of the contacts on a single progressive die which forms the

first contact shape **13** and second contact shape **23** simultaneously on a single chain of contacts. This allows for gang loading of an entire side of contacts on the first side or second side **35,36** of the insulator in one operation. The single progressive die allows for the production of these nonuniform contacts twice as fast as opposed to two separate progressive dies.

Once the electronic module **30** is removed from the electronic module socket **10**, the contacts **13,23** regain contact at their terminal sections **16,26** (FIG. 1). It is common for this cycle of insertion and removal of a circuit board from the electronic module socket **10** to occur in excess of 400 repetitions. In prior electronic module sockets this high number of cycles caused build-up of sufficient glass flakes from the electronic module **30** to inhibit the electrical connection between the first contact **13** and second contact **23**. Specifically, the build-up of debris is likely to occur at first and second module contact areas **15,25**. Due to the shape of the contacts **13,23**, the terminal sections **16,26** are only secondary areas where debris may build-up. Thus, the first improvement of this invention is the shape of the contacts **13,23** having the terminal sections **16,26** separate from the module contact areas **15,25**. This ensures a clean shorting area. The module contact areas **15,25** intercept the module first and upon complete insertion of the module, the terminal sections/short out connection areas **16,26** are pushed away from and external to the elongated central cavity **11** and avoid contact with the chamfered edge **34** of electronic module **30**. The second means of ensuring a clean shorting area is the nonuniform automatic wiping shape of the terminal sections **16,26** of the contacts **13,23**.

FIG. 4 shows a magnified view of the improved contact shape of the terminal ends **16,26** of first contact **13** and second contact **23**, respectively. FIG. 4 shows the contacts **13,23** after the electronic module is removed. The phantom outline depicts the contacts **13,23** just after removal of the module and the solid line indicates the location of the contacts **13,23** a moment later completely mated.

First contact **13** includes a first mast section **14** which is connected to a turn back loop section **6**, which is connected with first module contact area **15**, which is connected to semi-circle section **17** of the terminal section **16**. The second contact **23** includes mast section **24** connected with turn back loop section **7**, which is connected with second module contact area **25**, which is connected to the J-shaped section **27** of the terminal section **26**. J-section **27** of second contact **23** includes flat surface **28** at which sliding contact is made with an apex section **18** of the semi-circle area **17** of first contact **13**. The terminal section **16** of first contact **13** is connected to turn back loop section **6** via intermediate section **19**. The J-shaped section **27** of second contact **23** is connected to the turn back loop section **7** via intermediate section **29**.

Upon removal of a circuit board from between first contact **13** and second contact **23**, intermediate section **19** moves in direction of arrow **40** and intermediate section **29** of second contact **23** moves in direction of arrow **41**. The turn back loop sections **6,7** which act as spring members cause the intermediate sections **19,29** to spring back toward each other upon removal of the module. As the intermediate sections **19,29** move in direction of arrows **40,41**, respectively, the terminal sections **16,26** of the contacts **13,23** also move in correspondence with each other. Apex section **18** of the first contact **13** move in direction of arrow **42** while simultaneously, flat portion **28** of second contact **23** moves in direction of arrow **43**. Due to the nonuniform shape of the terminal sections **16,26** of the contacts **13,23**, a sliding

movement is set up at the terminal sections 16,26. This movement provides an automatic wiping area between the terminal sections 16,26 of the first contact 13 and second contact 23. The self-cleaning wiping action between the flat section 28 of the second contact 23 and the apex section 18 of first contact 13, removes any glass flakes or debris which may gather on the surface of the contacts 13,23. The wiping action of the terminal sections 16,26 assures that uninhibited contact is maintained and that a short out between the contacts 13,23 will occur at this short out connection area.

A normal force between terminal sections 16,26 is reached which is great enough to maintain a gap between module contact areas 15 and 25. The maintaining of the gap is required so that the collection of debris cannot prohibit the wiping motion and shorting connection at terminal sections 16,26.

The shape of the contacts having the terminal sections 16,26 separate and removed from the board contact sections 15,25 also limits the amount of glass flakes which gather at the short out terminal section 16,26.

FIG. 5 discloses an alternative embodiment of an electronic module socket including retention members 52,53 which act to retain contacts 13,23 from shorting out. The retention members 52,53 in a preferred alternate embodiment may be molded integrally with the insulator 12 and act to prohibit terminal sections 16,26 from contacting each other and shorting out. However, upon insertion of an electronic module the contacts 13,23 operate as discussed above, by having module contact sections 15,25 making electrical contact with the conductive surfaces of the electronic module. This alternative embodiment is useful in providing a simple, cost-effective method of providing either an entire electronic module socket or only a portion of an electronic module socket having nonshorting contacts, without having to use differently shaped contacts. Therefore, by addition of the retention members 52,53 to the insulator 12 the contacts 13,23 shaped to be shorting contacts act as nonshorting contacts.

It should be understood that various changes and modifications to the presently preferred embodiments described herein will be apparent to those skilled in the art. Such changes and modifications may be made without departing from the spirit and scope of the present invention and without diminishing its attendant advantages. It is, therefore, intended that such changes and modifications be covered by the appended claims.

What is claimed is:

1. An electronic module socket for interconnecting an electronic module to a circuit board, the electronic module socket comprising:

an elongated insulative housing including, an elongated central cavity for receiving an electronic module having;

a plurality of opposed contacts located along both sides of said central cavity configured to establish electrical contact with said electronic module upon insertion of said electronic module within said central cavity;

first and second contacts being correspondingly and non-uniformly shaped in order to provide a short out connection area; and

wherein self-cleaning of said short out connection area occurs as said first and second contacts move directly towards one another.

2. The electronic module socket of claim 1 wherein:

said first contact includes a semi-circular section having an apex point; said second contact having a J-shaped section having a flat area; and

upon removal of a module from said central cavity, said apex point slides against said flat portion.

3. The electronic module socket of claim 1 wherein: said first contact includes a first module contact area; a second module contact area of said second contact; and said first module contact area off-set from said second module contact area.

4. The electronic module socket of claim 1 wherein: said first and second contacts including terminal sections providing a wiping motion.

5. The electronic module socket of claim 1 wherein: said first contact includes a turn back loop section and a first mast section; and said second contact, includes a turn back loop section and a second mast section.

6. The electronic module socket of claim 1 wherein said first and second contacts are alternately mounted along each side of said central cavity.

7. The electronic module socket of claim 1 wherein said first and second contacts include contact tails for through-board insertion.

8. The electronic module socket of claim 1 wherein said first and second contacts include contact tails for surface mounting.

9. The electronic module socket of claim 1 wherein said insulative housing includes retention members for prohibiting said contacts from shorting out.

10. An electronic module socket insulator comprising:
a first contact having a terminal end;
a second contact having a terminal end;
said terminal ends of said first and second contacts providing for an automatic wiping motion upon removal of a module from between said contacts, said automatic wiping motion occurring as said first and second contacts move directly towards one another; and
said first and second contacts manufactured via a single progressive die.

11. The electronic module socket insulator of claim 10 wherein:

said first and second contacts are generated in a progression corresponding to the socket insulator so that said first and second contacts may be gang loaded.

12. An electronic module socket for interconnecting an electronic module to a circuit board, the electronic module socket comprising:

an elongated insulative housing including, an elongated central cavity for receiving an electronic module having;

a plurality of opposed contacts located along both sides of said central cavity configured to establish electrical contact with said electronic module upon insertion of said electronic module within said central cavity;

first and second contacts having a means for providing a short out connection area;

terminal section of said contacts not contacting said module upon its insertion within said central cavity; and

wherein self-cleaning of said short out connection area occurs as said first and second contacts move directly towards one another.

13. An electronic module socket for interconnecting an electronic module to a circuit board, the electronic module socket comprising:

an elongated insulative housing including, an elongated central cavity for receiving an electronic module having;
a plurality of opposed contacts located along both sides of said central cavity configured to establish electrical contact with said electronic module upon insertion of said electronic module within said central cavity; 5
first and second contacts being correspondingly and non-uniformly shaped in order to provide a short out connection area;
short out connection area of terminal sections of said contacts not contacting said module upon its insertion within said central cavity; and
wherein self-cleaning of said short out connection area 10 occurs as said first and second contacts move directly towards one another.

14. The electronic module socket of claim 13 wherein: said contacts include a terminal section positioned away from the plane of insertion of said module.
15. The electronic module socket of claim 13 wherein: a first contact includes a semi-circle area; an intermediate area; said semi-circle area in a non-linear orientation from said intermediate area;
a second contact includes an intermediate area and J-shaped section; and
said J-shaped section in a non-linear orientation from said intermediate area.
